UNITED STATES PATENT OFFICE.

DAVID GEESNER, OF WORCESTER, MASSACHUSETTS.

MEANS FOR COLD-PRESSING CLOTH.

1,095,568.

Specification of Letters Patent.

Patented May 5, 1914.

Application filed December 30, 1910. Serial No. 600,056.

To all whom it may concern:

Be it known that I, DAVID GEESNER, a citizen of the United States, and a resident of Worcester, in the county of Worcester and 5 State of Massachusetts, have invented certain new and useful Improvements in Means for Cold-Pressing Cloth, of which the following is a specification.

My invention relates to means for successfully cold-pressing cloth in a rotary press, which will enable even an inexperienced finisher to do it safely, and without getting into trouble, or spoiling the goods being treated.

Attempts made by me with rotary presses (such, for instance, as patented on August 6th, 1878, numbered 206,718) to cold-press cloth by feeding cold water through the second bed, and steam only through the cylinder and the first bed, resulted in failure because the heat from the hot cylinder and that contained in the cloth would, when the cloth reached the second or cold bed, cause water of condensation to form upon the 20 second bed to such an extent, and so fast, that after a few yards were passed through the machine, the material would commence to pucker and stick, and then refuse to pass out, becoming eventually torn and completely ruined. Similar results were had, though not quite as bad, when cold water was put into the cylinder, and steam only in the two beds. With a very light pressing merely, the cloth would pass through the 35 machine safely, but water of condensation would form so fast and in such quantity upon the cold surface of the cylinder as to spot the cloth and blotch it. So this, too, was given up as impractical.

I now have devised means to cold-press a piece of cloth successfully by making provision for removing the water of condensation forming upon the face of the cold, or chilled, pressing-member when in close proximity to a hot pressing-member, by taking care of it as fast as it forms thereon, and I do not moisten the cloth to such an extent as to cause it to stick during its passage through the machine, or to water-spot and become blotchy, and thereby unsalable. And I can do this while at the same time administering to the goods a very substantial pressing, instead of escaping disaster only by resorting simply to the lightest kind of 55 pressing, which was the best we were here-

tofore able to accomplish because of failure to solve the most essential question: how to dispense with the water of condensation inevitably forming very rapidly upon the cold pressing member, when opposed by a 60 hot pressing member.

The invention consists in the improvements to be fully described hereinafter and the novelty of which will be particularly pointed out and distinctly claimed. 65

I have fully and clearly illustrated my invention in the accompanying drawings to be taken as a part of this specification and wherein—

Figure 1 represents an end view of so 70 much of a rotary press as is needed to show the application of my invention to such a machine; Fig. 2 showing the opposite end view thereof. Fig. 3 is a top view of the parts required to carry out my invention; 75 and Fig. 4 is a front view thereof. Fig. 5 is a longitudinal section through the moisture-removing roll. Figs. 6 and 7 show means for bringing the roll shown in Fig. 5 into or out of contact with the cold-pressing cylinder of a rotary press. Fig. 8 shows the relation of certain details to each other. Figs. 9 and 10 show another detail in two different positions necessary for properly 80 handling the cloth. 85

Referring to the drawings by characters of reference, A is the cold-pressing cylinder of a rotary press, carrying next to its driving gear *a* between it and the frame B, another gear *b* which drives not only the 90 apron-draft-roll A', by meshing with the gear *c*, upon it, but also the gear *d* keyed to one end of an arbor *e*, that has fastened to its opposite end another gear *f*. The arbor *e* revolves freely in a bracket *g* fastened on to 95 top of frame, B, and the swing-arm *h* is strapped loosely to the bracket *g* by the caps *i*. Upon the opposite end of the machine there is fastened upon the top of frame B a bracket *g'* upon which swings the arm 100 *h'* held upon it by the caps *i'*. In the free ends of the swing-arms *h* and *h'* is mounted to rotate a cylinder C, held down by the caps *k* and *k'*, and between one end of the cylinder C and the swing-arm *h* it has fastened to it a gear *l* meshing with the gear *f*, which is fast upon the inside end of arbor *e*, so that, when the cold-cylinder A of the press revolves in the direction of the main driving gear *a* the cylinder C will turn in the same 110

direction, as indicated by the arrows, and its surface will wipe that of the cold-cylinder A.

B' is a hot pressing member preferably 5 in the form of a bed, and coöperating with a portion of the periphery of the cylinder A through an area of the latter preferably 10 to one side of the axis of rotation thereof, said bed being heated by any suitable and well known means, as, for example, steam admitted to the interior thereof. It will be noted that the cylinder C contacts the cylinder A on the opposite side of the axis of the latter from the bed B'.

15 Referring to Fig. 5, it will be seen that the cylinder C has perforated walls, thicker at one end than at the other, so that its interior flares toward the head-end C², which is provided with the head C' that is of larger 20 diameter than the opening at C² of the cylinder C, in order that any water in the interior of this cylinder can gravitate toward and run into the head C'. The opposite end 25 of the cylinder C is closed by the gear l which forms also the head C³ while the journal P', being made in one piece with head C³ and gear l, is sealed by plug P² screwed into the end of the journal P'.

Reaching into the head C' is a stationary 30 suction pipe D with its bent, or lowermost end D' reaching to a level somewhat below that of the opening C² in the cylinder C, so that any water that may get into the head C' will touch the mouth end D' of the pipe D, before it can reach as high as 35 the lowermost edge of the opening C². A bracket E juts out from the swing-arm h' to hold the U-piece, or pipe G flanged at H to the suction pipe D, and held down fast 40 by the clamp or cap F which is bolted to the bracket E.

J is a union which connects the U-piece G with the screw threaded end of the elbow-piece K, the opposite or smooth end of which 45 is being held in the bracket g' which forms an arbor for the swing-arm h', with its caps i' attached to it, to swing upon (see Fig. 8). A vertical pipe L attached to the elbow-piece K is connected at its other end to a suction 50 pump, not shown in the drawings, for removing not only what moisture might collect in the head C', but to create a vacuum in the interior of the cylinder C, which has its outer surface clothed with several layers 55 of absorbent cotton cloth M in order to cover the perforations M' in the cylinder C, so as to give the moisture absorbed by the cotton wrapper M from the wet surface of the cold-pressing cylinder, a chance to be withdrawn, together with the air, by the suction 60 pump just referred to. The packing nut N screwed upon the sleeve O screwed to the end of the journal P makes an air-tight joint between the interior of the head C' and the 65 suction pipe D, and the union J makes an

air-tight joint between the U-piece G and the elbow-piece K, held by the bracket g'.

While the suction cylinder C will remove the moisture formed upon the outside of the cold-pressing cylinder A more thoroughly when driven as just described, I can, particularly on light-weight goods, dispense with this gearing, and let the cylinder C simply revolve and be driven only by contact with the cold-pressing cylinder. 75

As to which method—the positively driven, or the frictionally driven—is preferable is best determined by the amount of moisture contained in the fabric that is to be cold-pressed. A fabric loaded with moisture before cold-pressing, will deposit very much more condensation upon the outside of the cold-pressing cylinder than the same fabric will do when fairly dry. Also, a light-weight fabric, even if given considerable moisture before cold-pressing, is less apt to wet the cold-cylinder as much as a heavy-weight cloth given about the same degree of moisture before cold-pressing, because the heavy-weight will hold and retain more of it. Therefore, I build my machine with the gear-drive shown, when excessive moisture is made, and leave it off on ordinary work, where the cloth is loaded with less moisture before cold-pressing and gives off less condensation to the chilled cylinder when contacting therewith. 80 85 90 95

In the practice of my invention, it is desirable, when stopping the machine, to raise the cylinder C from the position it occupied during cold-pressing, as shown in Fig. 6, to that shown in Fig. 7, so that the absorbent cotton wrapper M which becomes damp, and more or less wet during cold-pressing, will not remain in contact with the cylinder A 105 when the latter stands idle.

Although Figs. 6 and 7 show only one end of the machine it will be understood that what is said of this end, applies in the main to the opposite end, and a repetition 110 of the drawings appears therefore superfluous.

Referring to Figs. 6 and 7, h² is a bracket, fastened to the end of the swing-arm h', a duplicate of this bracket being also fastened to the end of the swing-arm h, at the opposite end of the machine, and a flat bar h³ extending across the machine is made fast to both to unite them. Behind the bar h³ is fastened a link n, one near each end of the machine, to which is hooked a hook m, at the end of a chain o, which runs over the sheaves p and q in posts Q. The other end of the chain o is secured to a sheave r fast upon the shaft s revolving in brackets z' at 120 the back of the post Q, one of which posts—as already stated—is fastened on top of the frames B at each end of the machine. 125

At the end of the shaft s extending beyond the post Q is keyed a gear t meshing 130

with a pinion u running on a stud u' secured to a bracket z^2 , and fixed to this pinion u is a hand-wheel v by turning which the shaft s can be caused to wind upon the sheave r , a part of chain o , or to unwind it therefrom; the shaft s carrying next to the frame B between it and the gear t a ratchet wheel z , with which coöperates a dog w swinging upon a stud w' , screwed into the frame B , in order to lock the ratchet shaft s in any position desired; for instance, that shown in Fig. 7. Thus, the cylinder C may be raised out of or lowered into contact with the cold-pressing cylinder 15 A whenever desired.

In my machine, patented August 4th, 1896, Number 565,072, the apron used is made of felt, which to a certain extent is elastic and yielding, and enough so, to allow dress-goods or light-weight fabrics to pass through the machine in a continuous manner; that is to say, with the ends of the pieces sewed together in order to make of them one continuous web of cloth, the impressions made by passing seams in the felt apron not being sufficiently deep to mark the goods so as to render them objectionable. Hence, generally, a leader is sewed on to the last piece of goods, as is customarily done 20 when running an ordinary rotary press with no apron, and this leader is left in the machine after the day's work is over, to sew onto it the following morning the first piece of another continuous web of cloth, consisting of many pieces of cloth sewed together 25 endwise, like above mentioned. This is done, to do away with introducing each piece of cloth singly, which, as the machine is now constructed, would cause quite a delay of time, because it being intended for 30 continuous use, no special provision is made to render the introduction of the cloth into the mouth of the machine particularly easy.

In my present invention I prefer to use a 35 cotton apron in place of the felt apron, as used in hot-pressing heretofore, because, to get the desired effect, I have to impart a harder pressing to the goods. And with the harder pressing, the goods cannot be 40 sewed together any more in a continuous web, because the seams would damage my cotton apron, which is un-elastic, and less thick than the felt aprons. Hence, when 45 cold-pressing with a cotton apron, I have to introduce each piece singly, to avoid cutting 50 the aprons, which a seam might do under severe pressure.

Referring to the drawings, the apron R after passing over the draft-roll A' , goes 55 down around idler rolls S and T , and coming up in front of the machine, goes over the front roller V to the cold-cylinder A . The front roller V (see Figs. 9 and 10) runs in swing-pads W , which turn on pivots or 60 studs W^2 , and have toothed segments or cir-

cular racks W' , into which mesh pinions X keyed upon shaft Z , which extends across the front of the machine and revolves in brackets Z' fastened to the frame B .

On one end of the shaft Z is fastened a 70 hand-wheel Y which has a couple of holes 1 and 2 drilled into the side of its rim. These holes 1 and 2 register with a catch pin 3 in order to hold the hand-wheel fast in the two positions shown in Figs. 9 and 10, the catch- 75 pin moving in a hole drilled into an arm projecting out from the bracket Z' .

By this means when the hand-wheel Y is turned to throw the apron roll V backward, as shown in Fig. 10, an open mouth or triangular pouch 4 is formed between the cylinder A and the apron R in its passage from the roll V toward the cold-cylinder into which mouth 4 the end of a piece of cloth can conveniently be placed by the operator, 80 and smoothed out by him to make sure of a proper start. When, after placing the smooth end of the cloth into this mouth, or pocket 4, the roll V is thrown forward again, as in Fig. 9, and the apron will hold 85 the cloth against the cylinder, so that when the machine is started and cylinder A and apron R move forward together, the cloth will be held flat and smoothly between the two when entering under the bed-plate pressure from the hot-pressing bed B . By the arrangement and mode of operation of the roll V on a swinging support, I am able to move the apron away from the pressing 90 cylinder without increasing the tension of 100 the apron, which is important in that it prevents undue strains on, and stretching of the apron.

Having thus described my invention, what I claim and desire to secure by Letters 105 Patent is:—

1. In combination, a cooled pressing cylinder, a hot bed coöperating with a portion of the periphery thereof, means for passing a web of cloth between said cylinder and bed, and means coöperating with the portion of the cylinder away from the bed for removing moisture from the cylinder. 110

2. In combination, a cooled pressing roll, a hot-pressing member coöperating therewith, and suction means for removing moisture from the surface of the cold-pressing roll. 115

3. In combination, a cooled pressing roll, a hot-pressing member coöperating therewith, a perforated roll having a covering of absorbent material to remove moisture from the pressing surface of the cooled pressing member, and suction means connected to 120 said perforated roll. 125

4. In combination, a cloth-pressing roll, and suction means for removing moisture from the pressing surface of the roll. 130

5. In combination, a cloth-pressing roll, and a perforated suction roll for removing 135

moisture from the pressing surface of the pressing roll.

6. In combination, a cloth-pressing roll, and a perforated hollow suction roll having a covering of absorbent material for removing moisture from the pressing surface of the pressing roll.

7. In combination, a revoluble cloth-pressing roll, and a revoluble perforated hollow roll having a covering of absorbent material adapted to contact the pressing surface of the cloth-pressing roll for removing moisture from the pressing surface of the pressing roll, and suction means connected with said perforated roll.

8. In combination, a revoluble cloth-pressing roll, a revoluble perforated hollow roll having a covering of absorbent material adapted to contact the pressing surface of said cloth-pressing roll for removing moisture from the said pressing surface, a chamber connected to said hollow roll, and means for removing moisture from said chamber.

9. In combination, a revoluble cloth-pressing roll, a revoluble perforated hollow roll having a covering of absorbent material adapted to contact the pressing surface of the cloth-pressing roll for removing moisture from the said pressing surface, a chamber connected to said hollow roll and concentric therewith, and means for removing moisture from said chamber.

10. In combination, a revoluble cloth-pressing roll, a revoluble perforated hollow roll having a covering of absorbent material adapted to contact the pressing surface of the cloth-pressing roll for removing moisture from the said pressing surface, a chamber connected to said hollow roll concentric therewith and of greater diameter than the same, and means for removing moisture from said chamber.

11. In combination, a revoluble cloth-pressing roll, a revoluble perforated hollow roll having a covering of absorbent material adapted to contact the pressing surface of the cloth-pressing roll for removing moisture from the said pressing surface, a chamber connected to said hollow roll, and suction means for removing moisture from said chamber.

12. In combination, a revoluble cloth-pressing roll, a revoluble perforated hollow roll having a covering of absorbent material adapted to contact the pressing surface of the cloth-pressing roll for removing moisture from the said pressing surface, a chamber connected to said hollow roll concentric therewith and of greater diameter than the same, and suction means communicating with said chamber outside the inner surface of said roll.

13. In combination, a revoluble cloth-pressing roll, a revoluble hollow perforated roll having a covering of absorbent material

adapted to contact the pressing surface of the cloth-pressing roll, said hollow roll being internally of a gradually increasing diameter from one end portion to the other, and suction means communicating with said hollow roll.

14. In combination, a revoluble cloth-pressing roll, a revoluble hollow perforated roll having a covering of absorbent material adapted to contact the pressing surface of the cloth-pressing roll, said hollow roll being internally of a gradually increasing diameter from one end portion to the other, a chamber carried by the end of larger diameter of said hollow roll, and suction means communicating with said hollow roll.

15. In combination, a revoluble cloth-pressing roll, a revoluble hollow perforated roll having a covering of absorbent material adapted to contact the pressing surface of the cloth-pressing roll, said hollow roll being internally of a gradually increasing diameter from one end portion to the other, a chamber carried by the end of larger diameter of said hollow roll, said chamber being of greater diameter than the greatest diameter of said hollow roll, and means for continuously withdrawing moisture from said chamber during the pressing operation.

16. In combination, a revoluble cloth-pressing roll, a revoluble hollow suction roll for removing moisture from the pressing surface of the pressing roll, said hollow roll being of a gradually increasing diameter from one end portion to the other, and means for collecting moisture at the end of the roll having the larger diameter said means consisting of a chamber revoluble with and concentric to the suction roll and of a greater diameter than the greatest diameter of said roll.

17. In combination, a revoluble cloth-pressing roll, a revoluble hollow suction roll consisting of a perforated shell having a covering of absorbent material in rolling contact with the cloth-pressing roll, a collecting chamber carried by said suction roll, said roll being adapted to cause the moisture therein to flow to said collecting chamber, and means for continuously removing moisture from the collecting chamber during the pressing operation.

18. In combination, a revoluble cloth-pressing roll, a revoluble hollow suction roll consisting of a perforated shell having a covering of absorbent material adapted to contact the cloth-pressing roll, a collecting chamber carried by the said hollow roll and of greater diameter than the roll, said roll being adapted to cause the moisture therein to flow to said chamber, and a suction pipe extending into said chamber and having its inlet end terminating outside the bore of the hollow roll.

19. In combination, a cloth-pressing roll,

a hollow suction roll adapted to contact the cloth-pressing roll to remove moisture therefrom, a connection for suction means communicating with said suction roll, and means for moving said suction roll toward and away from the cloth-pressing roll without cutting off the communication between said connection and suction roll.

20. In combination, a revoluble cloth-pressing roll, a revoluble suction roll adapted to contact the cloth-pressing roll, brackets on the frame, a swinging arm connecting one end of the roll with one of said brackets, a suction pipe entering the opposite end of 10 the roll and forming a pivotal connection between said end and the other bracket, and means for raising and lowering said roll.

21. In combination, a revoluble cloth-pressing roll, a revoluble roll having a covering of absorbent material arranged in rolling contact with said cloth-pressing roll to remove moisture from the surface of the cloth-pressing roll, and means for removing the moisture from said absorbent covering 20 during the pressing operation.

22. In combination, a revoluble cloth-pressing roll, a revoluble roll having a covering of absorbent material arranged in rolling contact with said cloth-pressing roll to remove moisture from the surface of the cloth-pressing roll, and means for continuously removing the moisture from said absorbent covering during the pressing operation.

23. In combination, a revoluble cloth-pressing roll, a revoluble roll having a covering of absorbent material arranged in rolling contact with the surface of said cloth-pressing roll to remove moisture from the surface of said cloth-pressing roll, a perforated shell supporting said absorbent material, and suction means for removing the moisture from said absorbent covering through the perforations of said shell.

24. In combination, a revoluble cloth-pressing roll, a revoluble roll consisting of a perforated shell having closed ends, a covering of absorbent material surrounding said perforated shell and covering the perforations thereof, said second roll being arranged with the absorbent covering in rolling contact with the cloth-pressing roll to take up moisture therefrom, and suction means communicating with the interior of 50 said second roll to remove moisture from the 55 absorbent covering through the perforations of the shell.

25. In combination, a revoluble cooled cloth-pressing roll, a hot pressing member coöperating therewith, a revoluble roll having a covering of absorbent material arranged in rolling contact with the surface of said cloth-pressing roll to take up moisture from the surface thereof, and means for removing the moisture from said absorbent covering during the pressing operation. 60 65

26. In combination, a revoluble cooled cloth-pressing roll, a hot-pressing member coöperating with said cylinder, and means for removing water of condensation from the pressing surface of said cylinder, said 70 means comprising a hollow revoluble roll having a perforated shell covered with absorbent material and contacting the pressing surface of said pressing roll, and suction means communicating with the interior of 75 said hollow roll, said hollow roll being closed except as to the perforations of the shell and the communication with said suction means.

27. In combination, a cooled pressing cylinder, a hot bed coöperating with the said cylinder to one side of the axis of revolution thereof, means for passing a web of cloth between said cylinder and bed, and means coöperating with the periphery of said cylinder on the opposite side of the axis thereof from the bed for removing moisture from the surface of the cylinder. 80 85

28. In combination, a cooled pressing cylinder, a hot bed coöperating with a portion 90 of the periphery thereof, means for passing a web of cloth between said cylinder and bed, and means coöperating with the portion of the cylinder away from the bed for continuously removing moisture from the cylinder. 95

29. In combination, a cooled pressing cylinder, a hot pressing member coöperating with a portion of the periphery thereof, means for passing a web of cloth between 100 said cylinder and member, and means coöperating with the portion of the cylinder away from the member for removing moisture from the cylinder.

In testimony whereof I have signed my 105 name to this specification in the presence of two subscribing witnesses.

DAVID GEESNER.

Witnesses:

M. E. McNINCH,
C. G. HEYLMEN.

It is hereby certified that in Letters Patent No. 1,095,568, granted May 5, 1914, upon the application of David Gessner, of Worcester, Massachusetts, for an improvement in "Means for Cold-Pressing Cloth," an error appears in the printed specification requiring correction as follows: Page 3, line 96, for the reference-letter "B" read *B'*; and that the said Letters Patent should be read with this correction therein that the same may conform to the record of the case in the Patent Office.

Signed and sealed this 26th day of May, A. D., 1914.

[SEAL.]

R. F. WHITEHEAD,
Acting Commissioner of Patents.
